No. 36,909.

Patented May 10, 1904.

UNITED STATES PATENT OFFICE.

WALTER H. DEUBLE, OF CANTON, OHIO.

DESIGN FOR A CUP.

SPECIFICATION forming part of Design No. 36,909, dated May 10, 1904.

Application filed October 19, 1903. Serial No. 177,708. Term of patent 7 years.

To all whom it may concern:

Be it known that I, WALTER H. DEUBLE, a citizen of the United States, and a resident of the city of Canton, county of Stark, and State of Ohio, have invented a new, original, and ornamental Design for a Cup, as shown in the accompanying drawings, in which—

Figure 1 is a perspective view of a cup, showing my design. Figs. 2 and 3 are similar views of the same from different points of view.

What I claim as new, and desire to secure by Letters Patent, is—

The ornamental design for a cup as herein shown.

WALTER H. DEUBLE.
